UNITED STATES PATENT OFFICE.

CHARLES E. HADLEY, OF NEW YORK, N. Y.

ADDRESSING-MACHINE.

SPECIFICATION forming part of Letters Patent No. 449,820, dated March 31, 1891.

Application filed November 22, 1890. Serial No. 372,311. (No model.)

To all whom it may concern:

Be it known that I, CHARLES E. HADLEY, a citizen of the United States, residing in the city, county, and State of New York, have invented certain new and useful Improvements in Addressing-Machines, fully set forth in the following description, and represented in the accompanying drawings.

This invention relates to a means for automatically setting a line of type in position for the purpose of printing therefrom; and it consists, briefly, in a plurality of perforated cards supported so that they may move one at a time into position for use, and in a plurality of plungers automatically moving against the perforated card that has been moved into position over them in such manner that the plunger or plungers opposite the perforations in the card will pass therethrough to operate a second plurality of plungers upon the opposite side of the card, which are thereby moved.

It consists, also, in a plurality of type-carriers or bars with means normally moving them simultaneously in one direction and adapted to be stopped by the plunger that is moved through the perforation of the card, the movement of said carriers being a yielding one, so that while one carrier is stopped the others may continue their motion until stopped by another plunger, or until they reach the limit of their stroke. With the type-carriers there is provided a means for inking the type-faces, and with an impression block or platen movable to and from the face of the type, and in the present construction also having means for carrying the article to be printed.

As a more ready understanding will be had by a detailed description of the improvement embodied in an automatic machine, such description will now be given, reference being had to the accompanying drawings, in which—

Figure 1 is a side elevation of the same, a portion of the frame being broken away to expose underlying parts. Fig. 2 is an end elevation thereof. Fig. 3 is a vertical cross-section taken on the line 3 3 of Fig. 1. Fig. 4 is an enlarged central sectional elevation taken on the line 4 of Fig. 2. Fig. 5 is a diagrammatic perspective view of the main instrumentalities, showing the position of the

type-carriers when a card perforated to spell the name "Smith" is in position. Fig. 6 is a perspective view of such card.

55

Referring to said drawings, it will be understood that the various parts of the machine are supported in a suitable frame-work A, having bearings for a driving-shaft 20, that receives continuous motion from a counter-shaft 21 through a pair of gears 22 23.

In the machine as at present organized there is provided at its front end a receptacle 30 for a stack of previously-perforated cards 31, that rest upon a movable base-plate 32, 65 adapted to slide upwardly with the cards in the receptacle 30. This base-plate is connected by a link 33 with the long end of a pivoted lever 34, the opposite end of which is provided with a weight 35, so positioned with 70 respect to the fulcrum of the lever that it exerts its greatest force while the receptacle 30 is filled with cards, such force gradually decreasing as the cards are moved from the receptacle, the upward movement of such cards 75 being effected automatically and without any positive feeding instrumentalities.

There is provided a receiving-receptacle 36, in which the perforated cards are delivered after they have effected one operation of the 80 machine. These cards are delivered upon a base-plate 37, moved downwardly as the cards are delivered thereon by means of a screw-threaded vertical spindle 38, that passes at its lower end through a nut revolved by a 85 worm-wheel 39, secured thereto from a worm 40, that is in turn continuously rotated by a belt 41, which passes around a pulley on the driving-shaft and around a similar pulley on the shaft of the worm 40. The stack of cards 90 31 is kept constantly pressed upwardly against the under surface of a frame 42, (see Fig. 4,) so that the upper card is in position to be carried along independent of the next card below it, and in being so carried along to its 95 operative position will simultaneously move the previously-positioned card over into the receiving-receptacle 36.

Interposed between the two receptacles 30 36 and immediately below the path of movement of the card being fed into operative position is arranged a number of series of spring-pressed plungers 43. These plungers are held by and adapted to reciprocate in

perforations in a fixed guide 19, the upper surface of which guide is substantially coincident with the under surface of the card that is moved into position over it, so that the card 5 will be properly supported by said guide. The plungers will be arranged in lines, each line containing plungers equal in number to, say, the letters of the alphabet and to the various other signs, punctuation-marks, &c., 10 that are necessary in composing, and there will be as many lines of plungers as will be required to set up a word or words in a line from which the impression is to be taken. Each of the plungers has comparatively large 15 bodies and are guided by the perforations in the guide 19 and have smaller heads adapted to extend through the perforation or perforations in the card and with reduced lower portions extending into perforations in a reciprocating head 44, a spring being interposed between each of the bodies of the plungers and the reciprocating head, by which all of the plungers upon the movement of the head will be pressed by yielding pressure against 20 the under surface of the card, so that those 25 for which there are no perforations for their heads to pass through will yield while the plunger carries the others upwardly, for which there are perforations provided.

30 Above the number of series of plungers 43, in the preferred construction, there is provided a second number of series of plungers 45, that are supported at their lower ends in perforations in the frame 42 and at their opposite ends in a similarly-perforated plate 46. Each of these second series of plungers is in line with the series of plungers below them, so that when one or more of the latter plungers project through perforations in the card 35 40 the corresponding plungers above them will be moved upwardly thereby. This second series of plungers are loosely mounted in their supporting-frame and plate, and rest by their shoulders upon the frame 42, with their reduced lower ends in alignment with the under surface of said frame, and thus upward movement will be imparted to them corresponding to the upward movement of the lower series of plungers that pass through 45 50 55 perforations in the card, less the thickness of the card, the distance between the two contiguous surfaces of the guide 19 and the frame 42 being simply enough to allow the movement of the card into and from position between them.

Above the second or intermediate series of plungers the type-carriers 50 are supported. These carriers are in the present construction a series of horizontally-arranged bars 18, 60 mounted to reciprocate over a pair of rolls 17 and under a guide-roll 16, and bearing upon their upper face type-faces corresponding to the characters that are required to be printed by the machine, such characters being equal 65 in number to the number of plungers in a line, before referred to. There will be as many type-carriers or bars in the machine as

there are numbers of series of plungers, and equal to the number of letters or words it is desired to print in a line, and these carriers 70 will be arranged compactly together, as shown in Fig. 3, so that the letters of a word will lie together or at the usual distance apart.

In order to extend each of the carriers in position to be acted upon by the plungers, 75 each bar is preferably provided with a supplemental bar 15, connected with the type-bar proper by an arm 14, which arm will converge from the supplemental bars to the type-bars in the manner shown in Fig. 3. Each 80 supplemental bar 15 moves with the type-bar and is guided in its movement by a groove in the upper surface of the plate 46, immediately above the ends of the intermediate series of plungers 45, and in similar grooves in a pair 85 of guide-bars 13. Each supplemental bar is provided at some suitable and predetermined point with a notch 12 upon its under side in position so that some one of the intermediate plungers 45 may project into said recess to 90 stop the movement of that bar and the type-carrier.

The operation of the instrumentalities so far described is such that when a card is moved into position above the number of 95 series of plungers 43 the head 44 will move upwardly, pressing the entire number of plungers against the under side of the card, and that plunger opposite which the perforation in the card occurs will be thereby projected through such card into contact with the end of the plunger located immediately above it, and continuing to move will also tend to move said intermediate plunger upwardly. As soon as this occurs the type-bars 100 will move bodily forward in the direction of the arrow, Fig. 4, and as soon as a notch in the supplemental bar coacting with that line of plungers arrives over the plunger that is tending to be forced upwardly such plunger 105 will immediately move upward into said notch and thereby stop the onward movement of that bar. Thus, as shown in Figs. 5 and 6, a card B is in position having a series of perforations located in such position therein 110 with respect to the characters upon the type-bars as will assemble a type on each of said bars in position to spell the name "Smith." The foremost bar is thus stopped by the end of an intermediate plunger in its notch, so as 115 to bring the letter "S" in printing-line. The next bar has been stopped by a plunger in the adjacent line to bring the letter "M" in such line and the succeeding bars have been similarly stopped by other plungers to bring 120 the letters "I," "T," and "H" in line. Above the type-bars is located an impression-block 125 130 135 140 145 150 155 160 165 170 175 180 185 190 195 200 205 210 215 220 225 230 235 240 245 250 255 260 265 270 275 280 285 290 295 300 305 their ends, which guards serve to support the article to be printed and also to prevent its contact with the type-faces not in printing-line. There is also provided an inking mechanism consisting of an inking roller or rollers 53, mounted at the end of a pair of swinging arms 54, that are adapted to move the ink-rollers over an ink-table 55 and onto the type-faces of the bars in advance of each printing movement of the impression-block. The face of the ink-table is curved in the arc of a circle with the axis of vibration of the ink-rollers as its center, and said table or its frame carries an ink-fountain 56 and supply-roll 57. As soon as the type-bars have come to rest, stopped in position by the several plungers with the proper type-faces in line, the ink-rollers move down and back to ink the type-faces, when the impression-block 51 then moves down and impresses the article—such as a newspaper, envelope, or slip—against the line of type-faces in printing position, printing said article and moving back to its normal position for the removal of said printed article and the feed of another article to be printed.

Any suitable motion may be imparted to the various instrumentalities so that they may operate automatically and in succession. Thus the cards are fed one by one from the receptacle 30 by a feeder consisting of a pair of arms 24, having at their ends a hook adapted to engage with the front edge of the card, and as the arms move rearwardly carry said card along with it over the number of series of plungers 43. Said arms are pivotally mounted at their rear ends to a reciprocating carriage 25, that is mounted upon a horizontal guide 26. Motion is imparted to said carriage 25 through links 28 from crank-disks 27, secured to the opposite ends of the driving-shaft 20. The reciprocation of the carriage 25 is also made the means for simultaneously moving the type-carriers forward, the connection therebetween being a yielding or slip one. Thus said carriage carries a number of rods 29, one for each type-carrier, the front ends of which rods pass through ears 11, projecting from the rear end of the supplemental bars 15. These rods 29 slide loosely through the ears 11, and are provided with springs in position between the carriage and the ears, so that the forward movement of the bars is had by the normal strength of the springs, and upon the stoppage of any bar its rod 29 will slide through its ear, compressing its spring, and thus permit the carriage to go on to move the remaining bars until they are stopped from time to time by a projecting plunger until the carriage arrives at the limit of its stroke. In the return movement of the carriage the rods will be drawn back until their heads meet the ears 11, when the type-carriers will be drawn back also. Motion is imparted to the platen 44 for moving the series of plungers upwardly from a suitably-shaped cam 10 fast to the driving-

shaft 20, that acts upon one end of a bell-crank lever 9, the other end of which is forked to engage the vertical spindle 8 of the platen 70 44. Motion is also imparted to the impression-block and ink-rollers from a pair of eccentrics 7, also secured to the driving-shaft 20, through eccentric straps and rods 6, connected to the hubs of the impression-block, which in turn is connected by links 5 with the short ends of bell-cranks supported by a rock-shaft 4, the long arms 54 of which carry the ink-rollers. 75

From the foregoing it will be understood that the organization provides a plurality of series of plungers, a plurality of type-carriers, there being a series of plungers for each type-carrier, the movement of any one plunger in a series forming a stop for the carrier, and 80 that particular plunger coinciding with a particular character upon the carrier and determining that that carrier will come to rest with that particular character in line for printing, and that the movement of any plunger in 90 each series is determined by a previously-perforated card that is interposed between the ends of the plungers and the type-carriers. Such an organization, therefore, is particularly adapted for use as an addressing-machine for addressing newspapers, letters, and 95 the like, and in such case the perforated cards will correspond, say, with the subscription list of a newspaper or magazine and will be held in stacks containing any suitable quantity of cards, each card being independent of the others, so that one card may be removed and others added or substituted therefor.

It will be understood that the invention is not limited to the particular form of type-carriers so long as each type-carrier carries a like series of characters movable toward their stopping positions and each carrier being adapted to be stopped independent of the others. It will also be readily seen that the intermediate series of plungers may be dispensed with and that the ends of the series of plungers 43 may in themselves form the stops coacting with the notches for stopping the type-carriers in proper position. 115

What is claimed is—

1. The combination, with a plurality of type-carriers, each bearing a like series of characters, of a previously-perforated card, a plurality of series of plungers coacting therewith and adapted to pass through the perforations of the card to determine the position of the type-carriers, inking mechanism for the characters, and an impression-block, substantially as described. 120

2. The combination, with a plurality of type-carriers, each bearing a like series of characters, and a reciprocating carriage common to said type-carriers for moving the same, of a previously-perforated card, a plurality of series of plungers coacting therewith and adapted to pass through the perforations of the card to limit the movement imparted to the type-carriers, inking mechanism for the 125 130

- characters, and an impression-block, substantially as described.
3. The combination, with a plurality of type-carriers, each bearing a like series of characters, a reciprocating carriage for moving the type-carriers, and yielding connections between said carriers and the carriage, of a previously-perforated card, a plurality of series of plungers coacting therewith and adapted to pass through the perforations of the card to limit the movement of the type-carriers, inking mechanism for the characters, and an impression-block, substantially as described.
4. The herein-described series of type-carriers rigid throughout their length, each carrier provided with a supplemental bar connected thereto at various angles, whereby the carriers may lie contiguous to one another while the supplemental bars are spread apart.
5. The combination, with a type-carrier bearing a series of characters, of a reciprocating carriage for moving the type-carrier, its connecting-bar 29, and intermediate springs, said connecting-bar having a head to return the type-carrier positively to its normal position, substantially as described.
6. The combination, with a plurality of type-carriers, each bearing a like series of characters, a plurality of series of intermediate plungers, and another plurality of series of plungers in alignment with the other series of plungers, a previously-perforated card adapted to be interposed between the two series of plungers, inking mechanism for the characters, and an impression-block, substantially as described.
7. The combination, with a plurality of type-carriers, each bearing a like series of characters, of a receptacle for a stack of previously-perforated cards, an automatic feeder for said cards, a plurality of series of plungers coacting with each card and adapted to pass through the perforations of the card to determine the position of the type-carriers, inking mechanism for the characters, and an impression-block, substantially as described.
8. The combination, with a plurality of type-carriers, each bearing a like series of characters, of a receptacle for a stack of perforated cards, an automatic feeder for moving the cards one by one into operative position, a plurality of series of intermediate plungers, and another plurality of series of plungers, between which the cards are fed, inking mechanism for the characters, and an impression-block, substantially as described.
9. The combination, with a plurality of type-carriers, each bearing a like series of characters, of a previously-perforated card, a plurality of series of plungers coacting therewith to determine the position of the type-carriers, inking mechanism for the characters, an impression-block, and a pair of carrying and supporting guards, substantially as described.
- In testimony whereof I have set my hand, this 31st day of October, 1890, in the presence of two witnesses.

CHARLES E. HADLEY.
